United States Patent

Des. 236,585
Patented Sept. 2, 1975

236,585

MULTIPLE UNIT CONTAINER FOR FLUIDS OR THE LIKE

Joseph M. Tabor, Toledo, and Robert W. Engel, Sylvania,
Ohio, assignors to General Mills Fun Group, Inc.,
Toledo, Ohio

Filed Oct. 23, 1973, Ser. No. 408,474

Term of patent 14 years

Int. Cl. D9—01

U.S. Cl. D9—18

—FIG. 1

—FIG. 5

—FIG. 2

—FIG. 3

—FIG. 4

FIG. 1 is a front quarter view in perspective of a multiple unit container for fluids or the like showing our new design;

FIG. 2 is a top plan view thereof;

FIG. 3 is a front elevational view thereof;

FIG. 4 is a bottom plan view thereof; and

FIG. 5 is a left end view in elevation thereof.

We claim:

The ornamental design for a multiple unit container for fluids or the like, as shown.
